Atty.

UNITED STATES PATENT OFFICE.

OTTO ASMUS WINTER, OF BUXTEHUEDE, PRUSSIA, GERMANY.

MACHINE FOR CUTTING WOOD INTO CHIPS.

SPECIFICATION forming part of Letters Patent No. 399,107, dated March 5, 1889.

Application filed May 28, 1888. Serial No. 275,271. (No model.) Patented in Germany March 24, 1887, No. 42,187.

To all whom it may concern:

Be it known that I, OTTO ASMUS WINTER, a subject of the Emperor of Germany, and a resident of Buxtehude, in the Kingdom of 5 Prussia, German Empire, have invented certain new and useful Improvements in Machines for Cutting Wood into Chips, (for which I have secured Letters Patent in Germany, No. 42,187, dated March 24, 1887,) of which the 10 following is a specification.

My invention relates to that class of machines which are used for rasping or shaving wooden blocks to make paper-pulp, or for reducing wood to small chips for dyeing and 15 tanning purposes; and the objects of my invention are, first, to afford means for producing chips of very regular form and size, and, secondly, to construct the shaving-drum in such a manner as to facilitate the replacement 20 and adjustment of the knives. I attain these objects by the mechanism illustrated in the accompanying drawings, in which—

Figure 1 is a front elevation of the shaving-drum, one-half of which is a section to the 25 line $x-y$ of Fig. 2, which is a side view of the drum, and Fig. 3 a detailed view in perspective of a knife and a compartment for the reception of the same.

Similar letters refer to similar parts throughout the several views.

The cutter head or drum is provided with a certain number of diagonal slots on its periphery, and each slot receives one knife or cutter, which occupies a corresponding position, all of said knives being at a uniform angle throughout their lengths. The periphery of the drum is provided with suitable solid 35 rings or collars for supporting the knives and increasing the stability of the drum, or it is composed of a number of correspondingly-formed staves or compartments, f , Fig. 3, for the reception of the knives. These helicoidal staves are provided with flanges c and d , by means of which they are bolted to two polyg-

onal disks or bottoms, A and B , the sides a a' a^2 a^3 and b b' b^2 b^3 of which correspond with the number of staves f and knives h . The knives are attached to the staves f by means of the cover-plates g and bolts i , and provided with slits h' , which allow the knives 50 to be withdrawn without removal of the cover-plates and to be adjusted in such a position that the knife-edges form the surface of a cylinder concentrically to the axis of rotation of the drum. The direction of the helicoidal 55 knife-edges is throughout the same, and the staves f , although fitting close together on one side, form such open canals that the chips of wood are compelled to leave the shaving-drum always on the same side at A . 60

To prevent the chips from falling into the inner space of the drum, the staves f on their back l and the cover-plates g are provided with corresponding notches, k , for the reception of narrow plates m , which serve to fill out 65 the remaining space between two adjacent staves carrying the knives.

Having now fully described and ascertained the nature of my said invention and in what manner the same is to be performed, what I 70 desire to claim and secure by Letters Patent is—

1. In a wood-shaving drum, the cutter head or drum having a series of diagonal slots in its periphery, the helicoidal staves, and the series of knives, substantially as set forth. 75

2. In a wood-shaving drum, the combination, with the cutter head or drum and the polygonal bottom pieces, A and B , of the helicoidal staves f and the knives h , substantially 80 as set forth.

In testimony that I claim the foregoing as my invention I have signed my name, in presence of two witnesses, this 3d day of April, 1888.

OTTO ASMUS WINTER.
